DOUBLE ACTING JOINT

Harold E. De Ment, Decatur, and Herschel L. Wisnasky, Forsyth, Ill.

Application July 21, 1948, Serial No. 147,703

Term of patent 7 years

(Cl. D54—2)

To all whom it may concern:

Be it known that we, Harold E. De Ment, and Herschel L. Wisnasky, citizens of the United States, residing at Decatur, in the county of Macon and State of Illinois, and Forsyth, in the county of Macon and State of Illinois, respectively, have invented a new, original, and ornamental Design for a Double Acting Joint, of which the following is a specification, reference being had to the accompanying drawings, forming a part thereof.

Figure 1 is a side elevational view,

Figure 2 is a top plan view, and

Figure 3 is an elevational view taken from the left-hand end of the Figure 2, showing our new design.

We claim:

The ornamental design for a double acting joint, as shown.

HAROLD E. DE MENT.
HERSCHEL L. WISNASKY.
